UNITED STATES PATENT OFFICE.

HARRY W. HILL, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

LENS POLISHER.

Application filed April 10, 1922. Serial No. 551,137.

This invention relates to new and useful improvements in polishers, and more particularly to a polisher especially adapted for use in polishing ophthalmic lenses, and the 5 like.

The main object of the invention is the provision of a polisher comprising a fabric base impregnated with a lens polishing material and attaching adhesive permanently 10 united with one face of the polisher whereby the polisher may be quickly and readily attached to a lens polishing machine.

Another object of the invention is the provision of a polisher for lenses consisting of a 15 fabric base having one face thereof impregnated with suitable abrasive material and the other face provided with an attaching adhesive, both faces of the polisher being embraced with a suitable protector which 20 will adhere to the faces and which can be readily removed prior to using the polisher.

A further object of the invention is the provision of a polisher comprising a reticulated fabric base impregnated upon one face 25 thereof with a pliable substance, together with an abrasive material and a suitable preservative for the pliable substance, and applying a suitable adhesive to the other face of the fabric, and a fabric protecting sheet 30 applied to both faces of the polisher and adapted to be removed prior to using the polisher.

Other objects and advantages of my improved construction should be readily apparent 35 by reference to the following specification taken in connection with the accompanying drawings, and it will be understood that I may make any modifications in the specific details of construction shown and 40 described within the scope of the appended claim without departing from or exceeding the spirit of my invention.

Figure I is a top plan view of a polisher constructed in accordance with my invention.

Figure II is a longitudinal sectional view 45 of the same.

Figure III is a similar view showing the application of the protecting fabric.

Fig. 4 is a view similar to Fig. II but on 50 an enlarged scale.

Fig. 5 is a view similar to Fig. III but on an enlarged scale, showing the protective covering for the polisher.

In carrying out my invention I have en-

deavored to provide a particular type of 55 polisher comprising a fabric base having one face thereof impregnated with a suitable waxy substance with abrasive material pressed into this substance and the other face of the polisher provided with a suitable adhesive whereby the polisher can be readily attached to any well known make of lens polishing machine.

In the accompanying drawings the number 1 indicates the fabric body, and I wish 60 it to be understood that this body can be made from any reticulated fabric, and particularly fabric wherein the warp and woof threads are of the same size and stripe woven tightly together so as to provide a resistance 65 against strain upon the fabric in any direction to thus provide a wearing surface which will be even throughout. One face of the fabric is first impregnated with a pliable substance, such as bees-wax, pitch, or the 70 like, and pressed into its pliable substance is a suitable abrasive material, it being preferred to use the regular polishing rouge which is well known in the lens polishing art. In order to provide for a suitable preservative to retain the waxy substance in 75 proper condition at all times, I mix with the wax or pliable substance a proper amount of methyl salicylate. This material is more commonly known as oil of wintergreen, 80 which, when added to a waxy substance, as in the present case, acts as a preservative by preventing fungus growth. Also, it renders the waxy substance more suitable for the 85 purpose by making it less brittle and more pliable, whereby it will quite easily conform to the shape of the lens being operated upon, and will also hold the abrasive better. In addition to the above or in place thereof may be added a phenolitic compound which will 90 produce a substantial amount of toughening to the pliable substance so that when the abrasive material is pressed into a waxy or pliable substance it will readily adhere to the 95 same.

In order to provide means whereby the polisher can be quickly and readily attached to a lens polishing machine, I impregnate the other face of the polisher with a suitable adhesive material, preferably an adhesive material which is insoluble in water, as a certain amount of water is used during the process 100 of polishing ophthalmic lenses and the like.

This adhesive may be gum dammar, rosin, or any other suitable adhesive well known in the art.

In forming my improved polisher I prefer 5 to use, as set forth above, a fabric wherein the warp and woof threads are arranged close together and even in weight throughout, and if found desirable the material can be of light or attractive colors. In impregnating 10 the material the wax or other pliable substance which may be used is pressed into the fabric in a semi-molten condition, and if found convenient the polishing or abrasive material can be intermixed with the pliable 15 material and the fabric impregnated with the various materials in a mixed state, although various ways and means can be employed for applying the various materials to the fabric.

20 In order to form a suitable protection for both faces of the polisher, that is, to protect the polishing face against gathering dirt particles, and also to prevent the adhesive side from sticking to an adjacent polisher, I 25 prefer to cover both faces of the polisher with a fabric material, preferably a close woven material, said fabric being applied to the polisher while the same is in a heated or sticky condition so that the fabric will readily 30 adhere to both faces of the polisher, this protective fabric will remain on the polishers until they are ready for use, and when ready for use the fabric can be loosened in any suitable manner at one edge and then readily 35 removed from both faces of the polisher.

In the drawings, in which I have endeavored to illustrate the invention, the wax and abrasive material is indicated at 2, arranged 40 upon one face of the polisher and the adhesive material indicated at 3 is arranged upon the opposite face of the polisher. The numeral 4 designates the fabric protecting cover which is applied to the faces 45 of the polisher, as set forth above.

While I have shown and described the preferred manner in which my improved polisher is formed, I wish it to be understood that various types of materials may be used 50 and various kinds of waxy substances im-

pregnated with an abrasive material can be applied to one face of the base of the polisher, while any suitable type of adhesive can be applied to the other side of the base, although it is preferred to have a type of 55 adhesive which is insoluble in water.

It is further to be understood that the fabric covering 4 preferably serves a double purpose in that it both protects the surface or surfaces of the polisher member, and also 60 serves to designate the particular grade or type of polisher and the manufacturer thereof. This, it will be noted, has been indicated in Figure I, the fabric coating 4 in this figure being shown as provided with the 65 words "70 mm. round" designating the size of the particular polishing, with the words "Rough polisher" denoting that the ingredients and embodiment of the material is in this particular device especially adapted for 70 rough polishing rather than for the finest finishing work, and in addition the device is shown as provided with the three letters "A O C" arranged in the form of a monogram forming the trade-mark of the manufacturer producing the article. These designations may be either merely imprinted upon the covering material 4, or may be printed and embossed thereon after the material is applied to the polisher, in which 75 event the polishing surface itself will be indented, as indicated at 6 in Figure III, these indentations removing a portion of the absolute center of the polisher and forming on its face ribs or indentations into which the 80 fluid used in polishing fits, and from which it works out between the polisher and material being polished so that these designations have the additional advantage of forming 85 fluid receiving recesses in the face of the 90 polisher, facilitating the actual polishing operation.

I claim:

As a new article of manufacture, a backing 95 provided with a coating of a mixture of beeswax, methyl salicylate and a phenol substance, and an abrasive embedded in the mixture.

HARRY W. HILL.
